CLAIM

The ornamental design for a filter element as shown and described.

DESCRIPTION

FIG. 1 a right elevational view is of a filter element showing our new design;

FIG. 2 is a left elevational view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a front and left perspective view thereof;

FIG. 8 is a front and right perspective view thereof; and,

FIG. 9 is a front, left, and bottom perspective view thereof.

The broken lines shown in the figures are for the purpose of illustrating portions of the filter element and form no part of the claimed design.

1 Claim, 9 Drawing Sheets
